DEFENSIVE PUBLICATION

UNITED STATES PATENT OFFICE

Published at the request of the applicant or owner in accordance with the Notice of Apr. 11, 1968, 849 O.G. 1221. Identification is by serial number of the application and the heading indicates the number of pages of specification, including claims, and of sheets of drawing contained in the application as originally filed. The file of this application is available to the public for inspection; reproduction may be purchased for 80 cents per sheet.

Applications published under the Defensive Publication Program have not been examined as to the merits of alleged invention. The Patent Office makes no assertion as to the novelty of the disclosed subject matter.

Class 260—53

No Drawing. 19 Pages Specification

An oxymethylene copolymer containing 80-99.5% molar of oxymethylene units and 0.1 to 20% of units —RO— derived from phenols. Preferred phenols have the formula

wherein X is halogen or nitro and Y is hydrogen, halogen or nitro. The polymers are made by polymerizing at least one mole of a cyclic oligomer of formaldehyde, e.g. trioxane with the corresponding phenol with a catalyst suitable for polymerizing trioxane.
